UNITED STATES PATENT OFFICE.

HARRY G. PARKER, OF LIBERTY, MISSOURI.

SEPARATING APPARATUS.

934,833.

Specification of Letters Patent. Patented Sept. 21, 1900.

Application filed January 9, 1903. Serial No. 409,917.

To all whom it may concern:

Be it known that I, HARRY G. PARKER, a citizen of the United States, residing at Liberty, in the county of Clay and State of Missouri, have invented certain new and useful Improvements in Separating Apparatus; and I do declare the following to be a full, clear, and exact description of the invention, such as will enable others skilled in the art to which it appertains to make and use the same, reference being had to the accompanying drawings, and to the figures of reference marked thereon, which form a part of this specification:

15 My invention relates to a separating apparatus, and more particularly to an apparatus of that class for use in chemical analysis wherein the separation of a precipitate is accomplished by centrifugal force.

20 In the separation of a precipitate in quantitative chemical analysis it has ordinarily been the custom to pass the liquid containing the precipitate through a filter of paper, asbestos, or other like material, which filter is 25 afterward either weighed with the precipitate, and allowance made therefor, or the filter is burned before the weight is taken. In either case the precipitate must be handled before the weight is taken, which together with the incident exposure to the air, presents an opportunity for loss in transferring, and oxidation, or from other causes.

It is the object of my invention to provide an apparatus wherein the solution may 35 be heated and precipitation accomplished without removal from the original container, from which the liquid may be removed after precipitation, and in which the precipitates may be weighed before being handled and 40 without exposure to the air, and without the use of the usual filter. In accomplishing this object I make use of an ordinary centrifugal machine, such as is used in making butter fat determinations and a specially 45 designed precipitation chamber which will be fully described and pointed out in the claims, reference being had to the accompanying drawings, in which like reference numerals refer to like parts throughout the 50 several views, and in which:

Figure I is a view, in front elevation, of an apparatus constructed according to my invention. Fig. II is an enlarged view, in side elevation, of one of the precipitation

jars. Fig. III is a central vertical section of same. Fig. IV is a top plan view of same. Fig. V is a view in side elevation of the standard yoke and a portion of the operating shaft. Fig. VI is a top plan view of the arm disk.

Referring more in detail to the parts:—1 designates the base portion and 2 the vertical standard of a centrifugal machine. Revolvably mounted in and projecting through the top of the standard 2 is the shaft 3, the lower portion of which revolves in an open yoke formed by dividing the lower end of the standard; and rigidly secured to said shaft and adapted for revolution within the open space between the yoke arms is a gear wheel 5. Journaled in a box 6 on base 1 is a laterally projecting shaft 7, having a gear 8 on its inner end and adapted to mesh with the gear on shaft 2, and a crank 9 on its outer end whereby the parts are operated. At the top of shaft 3 is rigidly mounted a disk 10, from opposite sides of which are projected the arms 11, and rigidly secured to the outer ends of said arms are the semicircular brackets 12; the arms and parts connected therewith being duplicates of each other; for which reason but one will hereafter be referred to in the description, with the understanding that such description refers equally to both. Projecting inwardly from the end of the bracket 12 are the pins 13, upon which is trunnioned a ring 14, and projecting through said ring is a jar 15, having a collar 16 adapted to seat against and support the jar from ring 14. Revolvably fitting within jar 15 is a container 17, preferably of the Bessemer converter shape, which is preferably supported on an inturned flange 18, preferably formed integral with the container. The container 17 is provided with a neck 19 which is adapted to fit snugly within or close to the mouth of a receptacle 20 when the latter rests directly on the bottom of jar 15. Around the joint between the container neck and the receptacle is preferably fitted a rubber or like sleeve 21 for the purpose of preventing leakage through the joint.

In operation, the liquid containing the precipitate or from which the precipitate is to be thrown down is placed in the container, and after precipitation is accomplished the container is whirled rapidly around by the

centrifugal machine. The precipitate being forced outward by the centrifugal force is guided by the sloping sides of the container into a receptacle where it is highly compressed by the force. After all the precipitate has been thrown down, the liquor may be removed by decanting, siphoning, or pouring as desired. Should any particles of the precipitate adhere to the sides of the container they may be loosened by a swabber introduced through the mouth of the container.

If it should be desired to wash the precipitate in some gas, or in a solution of some gas, the gas or solution may be introduced into the container and corked in. Then when whirled the precipitate or other compound in the container passes through the solution of the gas and is washed by it.

In case it should be desired to heat, cook, or boil some precipitate or compound the whole jar and container could be placed over the burner and the water introduced between the jar and container would act like the water cushion in the ordinary water bath, and the precipitate could be heated, etc., without being removed from the original receptacle, and the container in no more danger of breaking than flasks, etc., in the ordinary baths. The water cushion serves to equalize the pressure inside the container and receptacle, to prevent leakage and to render possible the use of a comparatively fragile material for container and receptacle. The level of the water cushion may be slightly higher than the level of the liquid in the container, so that the flow will be slightly inward thus washing the joint between the container and the receptacle from any portion of the precipitating liquid.

Having thus described my invention, what I claim as new, therein and desire to secure by Letters Patent is:—

1. In a separating apparatus, a container having a neck, and a detachable precipitate receptacle adapted to fit over said neck, for the purpose set forth.

2. In a separating apparatus, a solution container having a neck at one end, a detachable precipitate receptacle adapted for adjustment on said neck, means for holding said receptacle to said neck, and means for revolving said container and receptacle around a common center, for the purpose set forth.

3. In a separating apparatus, a solution container having a neck, a detachable precipitate receptacle adapted to fit over said neck, a collar adapted to engage a portion of said container and said receptacle, and means for revolving said parts, for the purpose set forth.

4. In a separating apparatus, a solution container having a neck, a detachable precipitate receptacle adapted to fit over said neck, and an elastic collar adapted to en-

gage a portion of said container and a portion of said receptacle, for the purpose set forth.

5. In a separating apparatus, a suitable jar, a solution container adapted to fit within said jar and having a detachable precipitate exit port, and a precipitate receptacle adapted to seat within said jar and cover the exit port in said container, substantially as set forth.

6. In a separating apparatus, a suitable jar, a solution container adapted to fit within said jar and having a detachable precipitate exit port, a precipitate receptacle adapted to seat on the bottom of said jar and having a mouth adapted to cover said exit port, substantially as and for the purpose set forth.

7. In a separating apparatus, a suitable jar, a solution container adapted to fit within said jar and provided with a precipitate exit port, a precipitate receptacle adapted to seat on the bottom of said jar and provided with a mouth adapted to cover the exit port in said container, and an elastic band covering a portion of both the container and the receptacle, substantially as and for the purpose set forth.

8. In a separating apparatus, a jar having an internal flange, a solution container located within said jar and seated against said flange, a precipitate receptacle seated on the bottom of said jar, and a neck on said container projecting into said receptacle, substantially as and for the purpose set forth.

9. In a separating apparatus, a jar having an internal flange, a solution receptacle located within said jar and seated against said flange, a detachable precipitate receptacle seated on the bottom of said jar, a neck on said container projecting into said receptacle, and means for actuating said jar, for the purpose set forth.

10. A separating apparatus comprising a centrifugal mechanism, a suitable jar carried by said mechanism and adapted for holding liquid and a solution container, and a receptacle within said jar for receiving precipitate from said container, said receptacle being adapted for attachment to and detachment from said container.

11. A separating apparatus comprising a centrifugal mechanism, a precipitate receptacle, and a solution receptacle having converging sides terminating in said precipitate receptacle, said receptacle being adapted for attachment to and detachment from said container.

12. A separating apparatus comprising a centrifugal mechanism, a water tight device adapted for carrying a solution container and a precipitate receptacle, a receptacle carried thereby, and a container carried by said device and provided with converging sides terminating in said receptacle, said recep-

tacle being adapted for attachment to and detachment from said container, substantially as and for the purpose set forth.

13. A separating apparatus comprising a centrifugal mechanism a jar containing liquid, a solution container located within said jar, and a precipitate receptacle located in said jar and connected with said solution container, both the container and receptacle being surrounded by the liquid contained

in said jar, said receptacle being adapted for attachment to and detachment from said container, substantially as set forth.

In testimony whereof I affix my signature in presence of two witnesses.
